UNITED STATES PATENT OFFICE

112,045

DESIGN FOR A CHILD'S CHAIR

George M. Roberts, Chicago, Ill., assignor to Continental Cushion Spring Company, Chicago, Ill., a corporation of Illinois

Application September 9, 1938, Serial No. 79,817

Term of patent 7 years

To all whom it may concern:

Be it known that I, George M. Roberts, a citizen of the United States, residing at Chicago, in the county of Cook and State of Illinois, have invented a new, original, and ornamental Design for a Child's Chair, of which the following is a specification, reference being had to the accompanying drawing, forming part thereof.

Fig. 1 is a perspective view of a child's chair looking at the front thereof and showing my new design.

Fig. 2 is a perspective view looking at the back thereof.

In the drawing the double lines represent welts.

I claim:

The ornamental design for a child's chair, as shown and described.

GEORGE M. ROBERTS.
